United States Patent Office

Des. 213,315
Patented Feb. 18, 1969

213,315

WHEEL

Donald J. Reid, Pleasant Ridge, Mich., assignor to Kelsey-Hayes Company, Romulus, Mich., a corporation of Delaware

Filed May 14, 1968, Ser. No. 11,912

Term of patent 14 years

U.S. Cl. D14—30

Int. Cl. D12—14

FIGURE 1 is a front elevational view of a wheel showing my design;

FIGURE 2 is a sectional view thereof taken along the line 2—2 of FIGURE 1; and

FIGURE 3 is a perspective view thereof, the view being on a reduced scale.

The stippled shading is shown to indicate a contrast in color.

I claim:

The ornamental design for a wheel, substantially as shown and described.
